UNITED STATES PATENT OFFICE

ALFRED GERMAN ROSE, OF GAINSBOROUGH, ENGLAND, ASSIGNOR OF ONE-HALF TO ROSE BROTHERS (GAINSBOROUGH) LIMITED, OF GAINSBOROUGH, ENGLAND, A BRITISH COMPANY

APPARATUS FOR CLOSING THE ENDS OF CARTONS OR LIKE RECEPTACLES

Application filed October 24, 1929, Serial No. 402,270, and in Great Britain October 26, 1928.

This invention is for improvements in or relating to apparatus designed for the purpose of closing the ends of cartons or like receptacles of the kind having a flap contiguous with one of the sides of the carton and arranged to be bent over the open mouth, and a strip along the free edge of the flap which is arranged to be bent over in the form of a tab and tucked between the opposing carton side and the contents.

This invention accordingly provides apparatus for the purpose specified, comprising in combination mechanism arranged to bulge one side of the carton away from the contents, folding means operable to fold down the flap upon the open mouth, and a tucking finger movable in synchronism with the folding means to insert the tab into the bulge aforesaid. Preferably, there is combined with apparatus as above described a conveyor which is intermittently movable to transport the carton along a path past a series of stations, at each of which one or more of the successive carton-closing operations are effected.

The bulging mechanism may comprise oscillating bulging members arranged to contact with and to exert pressure on those two opposed sides of the carton flanking the side portion with which the flap is contiguous and the folding means aforesaid may comprise tab-bending mechanism operable to bend the tab to a position substantially at right angles to the flap, a flap-turning member (e. g. the stationary plough 28) arranged to engage the flap and to turn it towards the open mouth of the carton, and a flap-closing member, operable in timed relationship with the tucking finger aforesaid to engage the surface of the partially closed flap and to fold it down upon the open mouth of the carton.

According to a subsidiary feature of this invention the tab-bending mechanism comprises a stationary abutment and an oscillating element movable towards and away from said abutment and arranged during its advance to bend the flap over the abutment. Further, locating members may be provided which are arranged to engage two opposed

sides of the carton and are intermittently operable in step with the folding means aforesaid to position the carton during the insertion of the tab. Preferably, these locating members are mounted for movement 55 with the flap-closing member aforesaid.

According to a further subsidiary feature, the conveyor is movable transversely to the carton path into the operative position, longitudinally to transport the carton, out of 60 the operative position in a reverse direction to its original movement and is returned parallel to the carton path to its first position.

One construction according to this invention will now be described with reference to 65 the accompanying drawings, in which—

Figures 1-6 show a carton in the various stages of closure;

Figure 7 is a general arrangement of carton-closing machine according to this invention; 70

Figure 8 is an elevation of the machine toward the right in Figure 7;

Figure 9 shows in plan the conveyor actuating mechanism; 75

Figure 10 is a continuation of Figure 9.

Figure 11 shows in plan certain parts of the folding mechanism.

In this machine, the cartons 20 partially folded as shown in Figure 1, are fed along 80 a channel 24 (see Figure 10); a second channel 25 leads at right angles from the first channel and the cartons are discharged into this second channel by an oscillating plunger 26 and are picked up by a conveyor 27. During 85 their intermittent transport by this conveyor the various folding operations are completed.

As seen in Figure 1, the closure flap 21 is bent outwardly from the carton 20. During 90 its movement along the second channel 25, this flap contacts with a twisted guide plate or plough 28 which bends it up to the position shown in Figure 2. At this stage the flap lies alongside an abutment 29, see Figures 7 and 11, and an oscillating tab folder 30 moves forward and bends the tab 22 over the abutment until it stands at right angles 95 to the flap.

A further movement of the carton brings 100

the flap and tab under a semi-circular guide plate 31 which maintains them in their correct angular position to each other and a continuation of the twisted guide plate 28 bends the flap over towards the open mouth of the carton; this stage is shown in Figure 5. At this point a pressure element 32 is moved forward into contact with the side 23 of the carton to compress slightly the contents. This pressure element 32 is mounted, with the tab folder 30 and a pair of forked bulging members 39 (whose functions are explained below) upon a bracket 33 which is pivoted at 34 to a lever 35 (pivoted on a shaft 49 on the machine bed) oscillated by a cam 36 and roller 37 the roller being maintained in contact with the cam by a spring which is not shown. The bracket is connected by a link 38 to the bed of the machine to ensure horizontal movement.

The bulging members 39 are advanced with the pressure element 32, and contact with the narrow sides of the carton next in advance (see Figure 11). Due to the convergent or forked shape of the bulging members these sides are pressed inwards, causing the side 23 to bulge outwards into a recess 74 provided in the channel.

Mounted for a vertical oscillation above the carton at the station at which the bulging operation is effected is a flap closing member 40 and a tucking finger 41. The flap closing member is mounted at 52 on the free end of an oscillating arm 42 which is linked at its far end 43 to a bracket 45 on the machine frame. Intermediate of the link 44 and the flap closing member 40 is pivoted at 46 a second link 47 connecting the arm 42 to a lever 48 mounted on a shaft 49 on the machine bed and having at its far end a roller 50 contacting with a cam 51 on shaft 102. A radius arm 100 connects the pivot 46 with an upstanding bracket 101.

The flap closing member is provided above its pivot 52 with a vertical extension 53, one side of which is in contact with a roller 54 on the machine frame. This arrangement ensures a correct movement of the flap closing member. The tucking finger 41 is mounted in a similar manner on oscillating arm 55, links 56 and 57 and lever 58 and is provided with a similar vertical extension 59 and roller 60. The flap closing member and the tucking finger are brought downwards at or about the same time, the first to press the flap 21 towards the open mouth of the carton and the second to insert the bent over tab 22 into the bulge between the carton side 23 and the contents. A pair of locating members 61, 62 arranged to contact with the leading and trailing sides of the carton to locate the latter during the operations just described are mounted upon the flap closing member 40.

The closing operation having been com-

pleted, the carton is traversed to a final station (shown in Figure 11) where a pusher 94 is operated by lever 95, roller 96 and cam 97 to eject the carton through an aperture in the wall of the channel 25.

The conveyor 27, which comprises a bar with a series of fingers 63 extending therefrom through a side wall of the channel 25 to engage the cartons, is operated with the pusher 26 as follows. The conveyor is pivotally attached at 98 and 99 to the lower arms 64, 65 of the pair of bell-crank levers whose upper arms 66, 67 are joined by a link 68. These bell-crank levers are pivoted at 69, 70 to a movable framework 71, an extension 72 of which carries the pusher 26.

The movable framework is jointed by a pivot pin 73 to an outer end of a roller arm 76, which is itself pivoted at 77 to the machine frame and is oscillated by a roller 78 cam 79 and a spring (not shown), the ends of which are hooked respectively to a stud 80 in the roller arm and a further stud 81 on the end of a motion arm 82. This motion arm is also pivoted at 77 to the machine frame and is provided with a roller 83 in contact with second cam 84 mounted with the first cam 79 on a continuously rotating shaft 85. The end of a projection 86 on the motion arm is held by the spring aforesaid in yielding contact with a stop 87 on the roller arm. The movable framework 71 is also pivoted at 88 to a second lever 89 jointed to the machine frame at 90 the arrangement of double levers giving substantially parallel movement. To the link 68 joining the upper arms 66, 67 of the two bell-crank levers carrying the conveyor is pivoted a lever 91, jointed to the frame at 77, and oscillated by a roller 92 and cam 93 mounted upon the shaft 85.

In the position shown in Figures 9 and 10, the movable framework 71 with the pusher 26 and the conveyor 27 is about to move horizontally to the right. At the end of its travel the cam 93 co-operates with roller 92 and lever 91 to rock the bell-crank levers 64, 66 and 65, 67 and to move the fingers 63 through the channel wall out of contact with the cartons. The conveyor in this retracted position and the pusher are now returned to the left, at which point the bell-crank levers are again rocked to bring the conveyor fingers through the channel into a position where they may engage the rear sides of fresh cartons.

The spring between the motion arm 82 and the roller arm 75 maintains the roller 78 in engagement with the cam 79 and also prevents the movable framework 71 being moved to the left by lever 91 when the latter is swung to move the fingers 63 into engagement with the cartons.

I claim:

1. A carton closing machine, operable on

cartons of the kind having a closure flap contiguous with one side of the carton for covering the open mouth, and a strip along the free edge of this flap to be bent over in the form of a tab and inserted between the opposing side of the carton and the contents, comprising the combination of an oscillatable pressure element and means to move it into contact with that carton side which is opposed to the flap to slightly compress the contents, oscillating grippers for exerting pressure on the two sides of the carton which flank the side opposed to the flap to bulge it away from the contents, folding means for folding the flap down upon the open mouth, a tucking finger, and means to move it in synchronism with the folding means to guide the tab into the previously formed bulge.

2. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of means for bulging this opposing side of the carton outwardly, a pressure element and means to move it previously to the bulging operation into contact with the opposed carton side to compress slightly the contents, folding means for folding the flap down upon the open mouth, a tucking finger, and means to move it in synchronism with the folding means to guide the tab into the previously formed bulge.

3. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of oscillating bulging members and means for moving them towards the carton to exert pressure upon the two sides of the carton flanking that side with which the flap is contiguous to bulge the carton side opposed to the flap away from the contents, tab-bending mechanism for bending the tab to a position substantially at right angles to the flap, and a flap-closing member operable to engage the flap and fold it down upon the open mouth with the tab in the aforesaid angular position and simultaneously to force the tab into the bulge aforesaid.

4. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of a pressure element and means for moving it into contact with the carton to compress slightly the contents, me-

chanical means for bulging the aforesaid opposing side of the carton outwardly, tab-bending mechanism for bending the tab to a position substantially at right angles to the flap, a flap-closing member operable to engage the flap and fold it down on the open mouth and simultaneously to force the tab into the bulge aforesaid, and a curved guide for maintaining the tab at right angles to the flap during the closing movement.

5. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of means for bulging this opposing side of the carton outwardly, a stationary abutment, an oscillating tab folder, means for moving the tab folder towards the abutment and thereby bending the tab over the abutment until it stands at right angles to the flap, folding means for folding the flap down upon the open mouth and means for forcing the tab into the previously formed bulge.

6. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of means for bulging this opposed side of the carton outwardly, a plurality of forked convergent shape and means for moving them towards the carton to wedge the latter within the fork, means for bending the tab to a position substantially at right angles to the flap, and means for turning the flap with the tab in said position down onto the open mouth of the carton and for inserting the tab into the previously formed bulge.

7. A carton-closing machine operable on cartons of the kind having a closure flap contiguous with one side of the carton for covering the open mouth and a strip along the free edge of this flap to be bent over in the form of a tab and inserted between the opposing side of the carton and the contents, comprising the combination of a conveyor for moving the cartons intermittently along a feed track, a plurality of fingers on said conveyor, means including a parallel-motion mechanism for moving the conveyor transversely of the feed track to insert a finger behind each carton, along the feed track to transport the cartons, transversely of the track to withdraw the fingers from engagement, and finally parallel to the feed track into its original position, a pressure element and means to move it into contact with the carton side to compress

slightly the contents, mechanical means for bulging the opposing side of the carton outwards away from the contents, folding means for folding the flap down upon the open mouth, a tucking finger and means to move it in synchronism with the folding means to guide the tab into the previously formed bulge.

In testimony whereof I affix my signature.

ALFRED GERMAN ROSE.
